HANDLE FOR COOKING POTS OR THE LIKE

J. Carroll Fletcher, Jr., Charleston, W. Va., assignor to
The Fletcher Enamel Company, Dunbar, W. Va., a corporation of West Virginia

Application February 10, 1956, Serial No. 40,105

Term of patent 14 years

(Cl. D44—29)

Figure 1 is a perspective view of a handle for cooking pots and the like embodying my new design;

I claim:

The ornamental design for a handle for cooking pots or the like, as shown and described.
